ALFRED HYMAN ANTHONY, OF COLCHESTER, ENGLAND.

FLOAT-VALVE FOR BOILER-FEED APPARATUS.

1,315,651.

Specification of Letters Patent. Patented Sept. 9, 1919.

Application filed May 22, 1918. Serial No. 236,052.

To all whom it may concern:

Be it known that I, ALFRED HYMAN ANTHONY, a subject of the King of England, residing in Colchester, Essex, England, have 5 invented certain new and useful Improvements in Float-Valves for Boiler-Feed Apparatus, of which the following is a specification.

This invention relates to float-operated 10 valves in boiler-feed apparatus of the type comprising a float-operated valve employed to control the escape of fluid that has leaked under high pressure past a piston which is a balancing or controlling piston for the 15 boiler-feed check-valve.

The float-operated valve referred to has heretofore been constructed as a needle-valve, having a conical point impinging upon a correspondingly coned seating, and 20 it has been found that such a needle-valve is liable to damage by being violently forced upon its seating, for instance under improper use of the testing handle provided for testing the freedom of the float, or 25 again, for instance, when the valve-box has been removed for examination and is carelessly replaced. Furthermore, when the valve-box is removed the said needle-valve is left exposed and projecting through its 30 guide and is so open to damage through careless handling.

The object of the present invention is to provide a construction in which the said liability to damage is obviated or reduced.

35 The present invention, therefore, resides in the selection for the float-operated valve in apparatus of the type defined, of a piston-valve of small diameter. The diameter may conveniently be about that of the 40 needle-valve above referred to as heretofore commonly employed. The selection of such a valve for the float-operated valve has not only the above referred to advantage of obviating the risk of damage, since 45 it does not have to impinge upon a seating which limits its travel, but the further advantage that, owing to its small diameter, it can be made sufficiently fluid-tight for the high pressure against which it operates and 50 yet be sufficiently free not to impair unduly the sensitivity of the action of the float. This is of importance since apparatus of the type defined frequently has to be relied upon to maintain the water-level 55 within less than half an inch from a normal value. It will be obvious that, as the pres-

sure against which the valve operates is frequently very high, as much as 250 lbs. to the square inch, it is not easy to obtain a valve which shall be both sufficiently fluid-tight and sufficiently free. 60

The fit of the piston of the valve above referred to must be exceedingly good so that it becomes necessary to exercise corresponding care with regard to a guide for 65 the piston, since any want of alinement of the latter with the axis of the piston will inevitably cause binding.

The present invention, therefore, provides, in apparatus of the type above defined, a 70 float-operated piston-valve of the said small diameter, and a guide therefor in combination with a seating for the valve and a guide-way for the guide, which seating and guide-way are both formed in a single 75 piece of metal. The object of this is to secure the advantage referred to with regard to accuracy of alinement.

By way of further description of the nature of this invention, one embodiment thereof is now described with reference to the accompanying drawing which is a vertical central section through the example given.

The top or cover of the float-box is indicated at A, portion of the float-arm at B, 85 and the pivot of the arm at C. The valve operated by the float is seen at D, D¹ and is in the form of two co-axial cylinders, one, D, of which is of small diameter, say about an eighth of an inch, and the other, 90 D¹, of which is larger, say about three-eighths of an inch. Where the parts D D¹ meet, a square shoulder D² is left. The portion D constitutes the valve and the portion D¹ its guide. The free end of the valve is 95 coned as at D³ or it may be rounded.

A combined guide-way and seating E is formed from a single block of metal by boring two co-axial cylindrical holes F, F¹ therein, a smaller, F, extending to one face of the block to constitute the seating for the piston-valve D and the other, F¹, extending to the other face of the block to constitute a way for the guide D¹. Extreme care is employed in the boring of these holes to insure their being a close and accurate fit on the parts they are intended to receive. Where the one cavity communicates with the other, the shoulder e so formed in the block is left square. About midway in the hole 100 F is an enlargement f from which a duct G passes through the body of the seating-block 110

to give communication with the outside of the block.

The block E is formed with a cylindrical stem E¹ and a conical head E². The latter is ground to make a steam-tight fit with a correspondingly-coned hole in the bottom of the valve-chest H, and the stem E¹ enters a hole in the cover A of the float-box, with which joint is made under the shoulder of the head E² in any convenient manner. The valve-chest H is bolted down on to the cover A by means not shown in the drawing, and so holds both joints steam-tight.

The valve-chest H has an inlet J for the leak-water from the boiler-feed and an outlet K communicating by a duct K¹ with an annular recess E³ in the block with which the duct G communicates.

The length of the head E² is made long enough to constitute a protector for the valve D even when the shoulder D² is home upon the shoulder e, in which position of the parts the valve D does not protrude above the face of the block E. The upper face of the latter is recessed as shown so that the actual seating surface of the hole F is less than it otherwise would be, while the end D³ is nevertheless always shielded.

The guide-portion D¹, above described as cylindrical, is not strictly so since one or more flats are formed on its otherwise cylindrical periphery, one of such flats being indicated at D⁴. The object of this flat, or these flats, is to prevent the steam-pressure with which the valve is urged upward from being applied to the whole area of the guide; the admission of the pressure to above the shoulder D² insures that the said pressure shall only be exerted on the relatively small area of the valve itself, D.

The coned or rounded end D³ of the valve facilitates its ready entrance into the seating. When, under the action of the float, it is so far withdrawn that the upper end gives communication for the leak-water to pass to the said enlargement f, the water can escape, but when the valve is moved upward from such a position it is closed. A further advantage obtained by the present invention is that, owing to the small diameter employed for the valve, it can be made sufficiently fluid-tight without sacrificing the requisite freedom to permit its being operated in a sensitive manner by the float.

Whereas it has been above stated that the seating and guide-way are formed in a single piece of metal, it is to be understood that the block E may be built up of more than one piece of metal provided these are so secured together, as for example by soldering, that they may be handled as a single piece in the machining operations required to form the seating F and the guide-way F¹. While it is desirable that the seating F and the guide-way F¹ should be machined at one op-

eration, it is essential that the two portions of the seating F, viz. the portion above the port f and the portion below it, should be thus manufactured since the whole success of the device depends upon accuracy of fit upon the plunger and alinement of these last said two holes.

What I claim as my invention and desire to secure by Letters Patent is:—

1. In apparatus for automatically controlling the flow of feed-water to a boiler, the combination of a valve-chest having an inlet, an outlet and a cylindrical port constituting a valve-seating arranged to put the said inlet into communication with the said outlet, a piston-valve co-operating with said seating, means for guiding the piston-valve coaxially with said port, and a float-arm operatively connected to the piston-valve, substantially as described.

2. In apparatus for automatically controlling the flow of feed-water to a boiler, the combination of a valve-chest having an inlet, an outlet and a cylindrical port constituting a valve-seating arranged to put the said inlet into communication with the said outlet, a piston-valve of a diameter less than three-sixteenths of an inch co-operating with said seating, means for guiding the piston-valve co-axially with said port, and a float-arm operatively connected to the piston-valve, substantially as described.

3. In apparatus for automatically controlling the flow of feed-water to a boiler, the combination of a valve-chest having an inlet and an outlet, a valve-seating block fitted into the wall of the valve-chest and having a cylindrical port constituting a valve-seating arranged to put the said inlet into communication with the said outlet, said block having a guide-way disposed co-axially with the said valve-seating, a piston-valve having one portion of small diameter co-operating with said valve-seating and another portion guided by said guide-way, and a float-arm operatively connected to the piston-valve, substantially as described.

4. In apparatus for automatically controlling the flow of feed-water to a boiler, the combination of a valve-chest having an inlet and an outlet, a valve-seating block fitted into the wall of the valve-chest and having a cylindrical port constituting a valve-seating arranged to put the said inlet into communication with the said outlet, said block having a cylindrical guide-way of a diameter larger than said port disposed co-axially with the said valve-seating, a piston-valve having one portion co-operating with said valve-seating and another portion of larger diameter guided by said guide-way, and a float-arm operatively connected to the piston-valve, substantially as described.

5. In apparatus for automatically controlling the flow of feed-water to a boiler, the

combination of a valve-chest having an inlet and an outlet, a valve-seating block fitted into the wall of the valve-chest, said block having a cylindrical bore which has one end 5 of smaller diameter constituting a valve-seating opening into the valve-chest and is connected at a point intermediate of its ends with said outlet and has its other end of larger diameter constituting a guide-way ar-

ranged co-axially with the valve-seating, a 10 piston-valve having one portion coöperating with said valve-seating and another substantially cylindrical portion of larger diameter guided by said guide-way, and a 15 float-arm operatively connected with said piston-valve, substantially as described.

In testimony whereof I affix my signature.
ALFRED HYMAN ANTHONY.
